US00D937655S

(12) **United States Design Patent** (10) **Patent No.:** **US D937,655 S**
Snodgrass et al. (45) **Date of Patent:** **** Dec. 7, 2021**

(54) **KNOB**

(71) Applicant: **dormakaba USA Inc.**, Indianapolis, IN (US)

(72) Inventors: **John Andrew Snodgrass**, Indianapolis, IN (US); **Michael Hans Viklund**, Indianapolis, IN (US); **Brendon Allen**, Indianapolis, IN (US)

(73) Assignee: **dormakaba USA Inc.**, Indianapolis, IN (US)

(**) Term: **15 Years**

(21) Appl. No.: **29/739,937**

(22) Filed: **Jun. 30, 2020**

Related U.S. Application Data

(62) Division of application No. 29/686,585, filed on Apr. 5, 2019, now Pat. No. Des. 891,901.

(57) **CLAIM**

The ornamental design for a knob, as shown and described.

DESCRIPTION

This application also incorporates by reference U.S. patent application Ser. No. 62/829,974, filed Apr. 5, 2019, titled Electro-Mechanical Lock Core, and U.S. patent application Ser. No. 62/829,768, filed Apr. 5, 2019, titled Electro-Mechanical Lock Core with a Cam Member Tailpiece, in their entirety.

FIG. 1 is a front perspective view of a knob in accordance with the present disclosure;

FIG. 2 is a rear perspective view of the knob of FIG. 1; FIG. 3 is a left side elevational view of the knob of FIG. 1; FIG. 4 is a right side elevational view of the knob of FIG. 1;

FIG. 5 is a front elevational view of the knob of FIG. 1; FIG. 6 is a rear elevational view of the knob of FIG. 1; FIG. 7 is a top plan view of the knob of FIG. 1; and, FIG. 8 is a bottom plan view of the knob of FIG. 1. Features shown in broken lines form no part of the claimed design.

1 Claim, 6 Drawing Sheets
